Specification for Design.

Patented Sept. 26, 1916.

Application filed July 12, 1916. Serial No. 108,965. Term of patent 14 years.

To all whom it may concern:

Be it known that I, JOHN LUPO, a subject of the King of Italy, residing in the city of New York, borough of the Bronx, in the county of Bronx and State of New York, have invented a new, original, and ornamental Design for Manicure Nail-Polishers, of which the following is a specification, reference being had to the accompanying drawing, forming part thereof.

The figure is a perspective view showing my new manicure nail polisher.

I claim—

The ornamental design for a manicure nail polisher, as shown.

JOHN LUPO.
